The ornamental design for a top assembly for a planer, as shown and described.

DESCRIPTION

FIG. 1 is a left side perspective view from the front of a planer showing my new design;

FIG. 2 is a rear elevational view of my new design;

FIG. 3 is a front elevational view of my new design;

FIG. 4 is a left elevational view of my new design; and, FIG. 5 is a right elevational view of my new design; and, FIG. 6 is a top plan view of my new design.

In the attached drawings, any broken line illustration is not part of the design sought to be patented. This design, however, is not limited to the exact details shown in the drawings, since equivalents and colorable imitations thereof will be evident to a person of ordinary skill in the art. Thus, within the scope of the appended claim, which is intended to cover only the ornamental and novel elements shown in the drawings, the invention may be practiced otherwise than as specifically shown and described herein.
